EXTRUDED PLASTIC SILL TRACK FOR A WINDOW UNIT

Dominique Dallaire and Raymond M. Dallaire, St. David,
Quebec, Canada, assignors to P.H. Plastics Inc., Lauzon,
Quebec, Canada

Filed Jan. 13, 1971, Ser. No. 106,297

Term of patent 14 years

Int. Cl. D25—01

U.S. Cl. D13—6

The figure is a view in perspective of the sill track of the present invention.

I claim:

The ornamental design for an extruded plastic sill track for a window unit, as shown.
